BATHTUB

John C. Chaffin, Selma, Calif.

Application January 7, 1950, Serial No. 7,053

Term of patent 3½ years

(Cl. D4—4)

To all whom it may concern:

Be it known that I, John C. Chaffin, a citizen of the United States, residing at 1954 High Street, in the city of Selma, county of Fresno, and State of California, have invented a new, original, and ornamental Design for a Bath Tub, of which the following is a specification, reference being had to the accompanying drawing, forming a part hereof.

Fig. 1 is a perspective view of a bath tub, showing my new design.

Fig. 2 is a top plan view thereof.

Fig. 3 is a side elevational view of the bath tub.

I claim:

The ornamental design for a bathtub, as shown.
JOHN C. CHAFFIN.
